PAPER ROLL HOLDER

Joseph Pfeifer and Marius Marrapese,
Cleveland, Ohio

Application June 16, 1937, Serial No. 148,554

4 Claims. (Cl. 242—55.2)

This invention, as indicated, relates to a paper roll holder. More particularly, it includes a receptacle made of a body section and a cover section each preferably formed of sheet material and having a member serving as a brace and also as a roll support. The invention also includes the method of forming and uniting the parts and engaging the roll supporting elements therein, as well as the combination of the structural features themselves.

The roll holder, while particularly intended for rolls of paper, such as toilet paper, paper towels and the like, is not to be wholly limited to such use, as it may be found of utility in holding rolls of paper with adhesive on one side for fastening paper wrappings on parcels, the smaller roll in the casing in such instance providing a moistening means. It also is adapted to hold cloth, or fabric tape, or for many similar purposes.

The principal object of the present invention is to provide a housing for paper rolls and the like which may be made of a minimum number of parts at low cost, and which at the same time will be a durable structure, of ornamental appearance, and adapted to withstand severe service without requiring replacement or repair.

Another object of the invention is to provide a structure adapted to receive a roll of paper within the same, such roll being supported so as to readily revolve when drawn upon at its free edge.

Another object of the invention is to provide a housing for a roll of paper, which may be formed with a body portion of sheet metal, a cover section of sheet metal, each having parts coacting to form a hinge, and having a bracing member which completes the housing structure and at the same time provides for the support and feeding of the paper roll.

Another object of the invention is to provide a unitary structure of sheet metal providing a brace for the housing and extension arms with means to receive the supporting bar for the roll of paper.

Another object of the invention is to provide a combined housing brace paper roll support and auxiliary roll support formed from a single sheet metal section.

Other and further objects of the invention will appear in the course of the following description.

To the accomplishment of the foregoing and related ends, said invention, then, consists of the means hereinafter fully described and particularly pointed out in the claims, the annexed drawing and the following description setting forth in detail certain structures embodying the

invention, such disclosed means constituting, however, but several of various forms in which the principle of the invention may be used.

In said annexed drawing:

Figure 1 is a front elevation, broken away in part, showing a structure embodying the principles of the invention;

Figure 2 is an end elevation of the structure shown in Fig. 1 looking in the direction of the arrows;

Figure 3 is a perspective view, broken away in part, showing the combined housing brace, paper roll holder, and auxiliary roll holder, with the roll supporting bars in position;

Figure 4 is a fragmentary view of portions of the body and cover members of the housing illustrating the method of forming the hinges; and

Figure 5 is a fragmentary view showing the end portion of the structure illustrated in Figure 4.

As is clearly shown in the drawing, the device comprises a housing or casing 1 having a body portion 2, a cover portion 3, and bracing member 4. The body portion is formed of sheet metal bent to provide a back wall 5, and two side walls 6, 7. The side walls at their forward free edges are curved on a long radius to afford a support for the curved cover member presently to be described. The back wall is preferably provided with a rearwardly offset area to form an open loop 8 which may engage over an upwardly directed bracket member (not shown), such bracket being secured to the wall or some other point of support. The body portion is entirely open at the bottom, there being no bottom wall, but merely the back wall and two side walls, above referred to. A plurality of screw holes 9 may also be provided as alternative means for securing the device to a point of support. In the latter instance, the device is not readily removable as is the case when the loop and bracket method of supporting the housing is employed.

The cover member 3 is preferably formed of a blank of sheet material of rectangular shape bent along a curve of large radius so as to fit closely the curved edges of the side walls of the body heretofore described. It may be single or composite, such as a metal frame having a transparent or translucent panel. In order to provide an ornamental effect to the outer surface of the cover and at the same time reinforce the same, a pair of narrow parallel metal strips 11 are engaged centrally of the cover member, being held frictionally by the engagement of inturned ends on said strips or by welding or otherwise. In

place of strips, ribs may be formed in the metal of the cover by stamping, such ribs preferably being at approximately the positions of the strips 11. The lower end of the cover member is curved 5 inwardly and has in effect a gripping action on the adjacent portions of the body member 2.

The upper rearward edge of the cover is provided with hinge members in cooperation with companion hinge members at the upper edge of 10 the back of the body member. These hinge members on the cover may be in the form of curved ears 12 bent inwardly toward the under side of the cover after passing through marginal apertures 13 in alignment therewith formed adjacent 15 the top edge of the back wall of the body member immediately below a beaded or inturned top edge 14, as best seen in Figures 4 and 5.

In order to firmly position the free forward edges of the side walls of the body, a bracing 20 member 4 is provided, such member being formed of a sheet metal strip of special shape and notched and shaped in the manner best seen by reference to Figure 3 of the drawing.

Thus, it will be noted that the bracing strip 25 has a forward section 15 of full width but severed at the lower front edges from the metal of the side portions 16, 17, which are also formed with slits parallel to the bottom to provide resilient projecting strips 21, 22, which are shortened at 30 their free ends to permit the upper areas of the side portions to be bowed outwardly from the general plane of each side to form contacting and securing portions 18, 19, for fastening the bracing member 4 by welding or by any other 35 suitable fastening means to the forward lower inner surfaces of the side walls 6, 7, of the body.

The resilient projecting strips 21, 22, are provided with apertures 23, 24, to receive the reduced shaft ends of a roller 25, said apertures 23, 40 24, preferably somewhat elongated and inclined slightly downwardly to provide a limited degree of frictional contact of the roller 25 with the free end of the paper as it is being withdrawn. This roller 25 may be a hollow perforated metal 45 roller carrying some material having an agreeable odor, or when the device is to be used as a moistener, may be used as a perforated moisture channel. It may in such case be covered with sponge rubber and a moisture supplying conduit 50 may engage through the ends of the roller, having a rotatable connection of conventional form.

The side portions of the bracing member 4 beyond the position of the projecting strips 21, 22, 55 are of full width but have beveled ends providing short horizontal top edges which are formed with recesses or notches 26 within which the ends of the paper roll support bar 27 are received. At points spaced from the ends of the bar 27, disk-like members 28 are provided, such members 60 preferably being cup-shaped members which may readily engage within the hollow tubular core of the paper roll (not shown).

It will be obvious that when the casing is to be 65 used for paper towels or the like it will be longer and narrower than when used for narrow material such as toilet paper. The free edge of the paper on the roll is preferably threaded between the auxiliary roll 25 and the front section 15 of the bracing member 4. The free end of the paper projects below the open underside of the body portion of the device, as there is no bottom wall whatsoever. The auxiliary roll 25 is engaged 70 between the resilient strips 21, 22, by spreading the latter apart and engaging the ends 75

of the shaft in the apertures provided in said strips.

The paper roll can be readily placed in or removed from the housing by lifting the cover 3. The ends of the bar 27 fit freely within the 5 notches 26 of the bracing member 4. When the roll is to be inserted, the bar 27 is first engaged centrally of the tubular core of such roll and the projecting ends of the bar are then dropped into the notches. 10

The action of the roll 25 has already been indicated in part. It might be explained that where it is desired to impart an agreeable odor to the paper being withdrawn and the room in general, the action of drawing on the free end of the paper on the roll will rotate and agitate the roller 25 and cause it to actively impart the odor to the paper passing therereover. This is a more effective means of disseminating the odor than where the roll supporting member 27 is made 20 hollow. The roll 25 may have its outer surface formed of compressed odor-imparting or germicidal material. In place of a single roll 25, two closely spaced parallel rolls may be provided, the free end of the paper roll in such instance being 25 threaded between such rolls, which would be supported in pairs of oval apertures in the ends of the resilient projecting strips 21, 22, respectively.

Other modes of applying the principle of our 30 invention may be employed instead of those explained, change being made as regards the structures herein disclosed, provided the means stated by any of the following claims or the equivalent 35 of such stated means be employed.

We therefore particularly point out and distinctly claim as our invention:

1. A housing for a paper roll comprising a member of sheet material providing a back and side walls, a member of sheet material providing 40 a cover section over the top and front areas of said first-named member, and a combined bracing and roll supporting member, the roll supporting member being formed with a central portion serving as a bracing member connected to 45 the forward free ends of said first-named member adjacent the lower portion thereof and having inwardly extending arms displaced inwardly from said side walls, and means on said extending arms to cooperate with a paper roll supporting 50 roller.

2. A housing for a paper roll comprising a member of sheet material providing a back and side walls, a member of sheet material providing 55 a cover section over the top and front areas of said first-named member, and a combined bracing and roll supporting member, the roll supporting member being formed with a central portion serving as a bracing member connected to the forward free ends of said first-named member 60 adjacent the lower portion thereof and having inwardly extending arms displaced inwardly from said side walls, and means on said extending arms to cooperate with a paper roll supporting roller, and having extension arms associated with 65 said first-named arms to support an auxiliary roller.

3. A housing for a paper roll comprising a member of sheet material providing a back and side walls, a member of sheet material providing 70 a cover section over the top and front areas of said first-named member, and a combined bracing and roll supporting member, the roll supporting member being formed with a central portion serving as a bracing member connected 75

to the forward free ends of said first-named member adjacent the lower portion thereof and having inwardly extending arms displaced inwardly from said side walls, and means on said 5 extending arms to cooperate with a paper roll supporting roller, and having extension arms associated with said first-named arms to support an auxiliary roller, such auxiliary roller being disposed in spaced relation to another element of 10 said combined bracing and roll supporting structure to receive the free end of the paper roll intermediate the same.

4. A housing for a paper roll comprising a member of sheet material providing a back and 15 side walls, a member of sheet material providing a cover section over the top and front areas of said first-named member, and a combined

bracing and roll supporting member, the roll supporting member being formed with a central portion serving as a bracing member connected to the forward free ends of said first-named member adjacent the lower portion thereof and 5 having inwardly extending arms displaced inwardly from said side walls, and means on said extending arms to cooperate with a paper roll supporting roller, and having extension arms associated with said first-named arms to support 10 an auxiliary roller, such auxiliary roller being disposed in spaced relation to the central section of said combined bracing and roll supporting structure to receive the free end of the paper roll intermediate the same. 15
